UNITED STATES PATENT OFFICE.

ALBERT B. VARBLE, OF DAYTON, OHIO, ASSIGNOR TO ABRAM L. ZENT, OF DAYTON, OHIO.

VENDING MACHINE.

Application filed June 25, 1923. Serial No. 647,552.

This invention relates to a machine for vending postage stamps and the like.

One object of the invention is to provide a machine which will positively and accurately 5 deliver a selected number of postage stamps, or other articles connected one to the other in strips; to this end a further object of the invention is to provide in such a machine an improved coin controlled device which 10 will positively control the amount of movement imparted to the strip or strips by the feeding devices.

Another object of the invention is to provide a machine of this kind which will deliver stamps, or other articles, of any one of 15 a plurality of denominations or kinds at the option of the purchaser.

A further object of the invention is to provide a machine of this kind which will be 20 simple in its construction, positive in its operation and can be produced at a relatively low cost.

Other objects of the invention will appear as the mechanism is described in detail.

In the accompanying drawings Fig. 1 is a front elevation, partly in section, of a machine embodying my invention, showing a portion only of the cabinet; Fig. 2 is a rear elevation of the same, partly broken away; 25 Fig. 3 is a top plan view of the same; Fig. 4 is a transverse sectional view taken on the line 4—4 of Fig. 2; Fig. 5 is an elevation of the left hand end of the machine, as shown in Fig. 1; Fig. 6 is a detail view of the coin controlled connecting device; Fig. 7 is a sectional view taken on the line 7—7 of Fig. 5; Fig. 8 is a vertical section taken on the line 8—8 of Fig. 2, looking in the direction of the arrows; Fig. 9 is a detail sectional view of 30 the yoke supporting shaft showing the manner of mounting the yokes thereon; Fig. 10 is a detail view of the coin controlled connection between the actuating device and the controlling device, showing the connection established for delivering ten cents' worth of stamps; Fig. 10^a is a detail; Fig. 11 is a similar view showing the connection established for delivering five cents' worth of 35 stamps; Fig. 12 is a detail view of the lock for rendering the feeding mechanism normally inoperative; Fig. 13 is a sectional detail view of the controlling device; Fig. 14 is a detail view of the cutter; Fig. 15 is a side elevation of a modified form of the coin controlled device; Fig. 16 is a plan view of

the same; and Fig. 17 is a detail view of the actuating arms and their controlling cams for this modified form of the device. Fig. 18 is a detail view of one of the roller supporting yokes and its actuating cam. 60

In these drawings I have illustrated one embodiment of my invention and have shown the same as comprising a main frame consisting of end members 1 and 2 connected one to the other by tie bars 3, 4, and 5, and by a front plate 6. This main frame is mounted upon a base 7 and is enclosed in a casing 8, a portion of the rear wall of which is movable and constitutes a closure 9 by means of which access may be had to the interior of the casing. Means are provided for supporting within this casing a plurality of strips of postage stamps, or other articles connected in strips, which are to be vended. While the machine is designed primarily for 70 vending postage stamps it will be understood that it may be utilized for dispensing various articles which are connected one to the other in the form of elongated strips or webs such, for example, as tickets and savings 75 certificates. The term "stamp" or "stamp strip" as herein used is intended to include not only postage stamps but any such similar articles. 80

The present machine is designed to deliver 85 at the option of the purchaser a selected number of stamps of a selected denomination. To this end the machine is provided with means for supporting therein strips of stamps of different denominations, in the present instance one cent stamps and two cent stamps, and is provided with separate coin controlled mechanisms for controlling the delivery of stamps of the respective denominations. These mechanisms are mounted on the main frame and, as shown in Fig. 1, the mechanism for controlling the delivery of one cent stamps is at the right hand end of the machine and the mechanism for controlling the two cent stamps is at the left 90 hand end of the machine. The controlling mechanisms are substantially identical with the exception that the mechanism for controlling the delivery of one cent stamps has means for controlling two strips of stamps 95 while the mechanism for the two cent stamps is designed to control but a single strip of stamps. Each coin controlled mechanism comprises a vertically arranged coin chute 10 having a forward extending portion 11 100

which communicates with a slot in the front wall of the casing 8, through which the coins may be deposited in the coin chute.

Postage stamps when furnished in strips are usually wound in rolls and in these drawings I have shown three rolls of stamps, 12, 13, and 14, loosely mounted on a shaft 15 extending lengthwise of the machine and, in the present instance, mounted in brackets 16 on the forwardly extending portions 11 of the coin chutes. One of these rolls, 12, consists of two cent stamps and the other two rolls, 13 and 14, consist of one cent stamps. The web or strip of stamps is carried from each roll downwardly through a suitable guideway 17, which, as here shown, is formed between the front plate 6 of the main frame and a supplemental plate 18 rigidly secured thereto and spaced therefrom by projections 19 which also serve to divide the space between the plates 6 and 18 into three separate guideways. Preferably the rear wall of the guideway, that is, the wall adjacent to the gummed side of the stamps is serrated or provided with longitudinal ribs 20 having narrow contact edges with which the stamps engage and to which they are not likely to adhere. Near the lower end of each guideway 17 is a pair of feeding rollers 21 and 22, the roller 21 being preferably provided with a rubber facing. The rollers 21 for the several strips of stamps are preferably operated in unison and, as here shown, they are rigidly secured to a shaft 23 journaled in bearings 24 of the main frame and provided with means for rotating the same. In the present instance, one end of the shaft 23 extends through one of the end walls 8 of the casing and has secured thereto an operating handle or crank 25. The second feed roller 22 of each pair constitutes a pressure roller and the several rollers 22 are independently movable into and out of operative relation with their corresponding positively driven rollers 21. As here shown, each roller 22 is mounted on the forward arm 26 of a yoke 27 which is pivotally mounted at its upper end on a shaft 28 extending lengthwise of the main frame and mounted in the walls 1 and 2 thereof. Each yoke is acted upon by a spring which tends to move the same and the roller 22 carried thereby, forwardly and into operative relation with the corresponding feed roller 21. As here shown, a coil spring 29 is interposed between the rear arm 30 of the yoke and the tie bar 4 of the main frame. This spring is preferably adjustable and to accomplish this I have mounted in the tie bar 4 a screw threaded stud or pin 31 having on its inner end a collar 32 against which the end of the spring 29 bears. By adjusting the position of this stud or pin on the main frame the tension of the spring may be regulated to vary the pressure of the roller 22

against the roller 21. Extending lengthwise of the main frame and between the two arms of the several yokes 27 is a cam shaft 33 and rigidly secured to this shaft and adjacent to each yoke is a cam 34 adapted to act upon the rear arm of the yoke and force the same rearwardly against the tension of the spring 29. In the present instance, a screw threaded stud 35 is adjustably mounted in the rear arm of the yoke and has its inner end tapered to engage the cam projection 34. By adjusting the stud 35 with relation to the yoke arm the amount of movement imparted to the roller 22 may be regulated. The cam shaft 33 is driven from the shaft 23 of the feed rollers and to this end the latter shaft has secured thereto a gear 36 which meshes with a gear 37 which is secured to the cam shaft 33. The gears are, in the present instance, of such a ratio that the feed rollers 21 will make one and one quarter revolutions for each complete revolution of the cam shaft; this being done to cause the stamp strips to be advanced the desired distance upon each complete revolution of the cam shaft. The pressure rollers 22 are preferably locked normally in their retracted or inoperative positions and the locking means is of such a character that the pressure rollers for the two cent stamps and for the one cent stamps are separately locked and can be separately released. To this end the yoke 27 of the two cent stamp roller is carried by a sleeve 38 mounted on the shaft 28, as shown in Fig. 9, and journaled in the end member 2 of the main frame, the sleeve forming the bearing for the shaft and having movement relatively thereto. The yokes 27 for the respective pressure rollers for the one cent stamps are carried by sleeves 38 and 39, respectively, the sleeve 38 being rigidly secured to the shaft 28 and the sleeve 39 being loosely mounted on the shaft 28, thus permitting the two pressure rollers for the one cent stamps to have movement relatively one to the other to enable them to be properly adjusted. In order that the intermediate yoke 27 carried by the sleeve 39 may be locked in its retracted position I have provided the sleeve 39 with an upwardly extending arm 40, the upper end of which lies in front of an obliquely extending arm 41 extending upwardly from the sleeve 38 so that when the sleeve 38 is rocked in a direction to retract its pressure roller the arm 41 will engage the arm 40 and cause the retraction of the pressure roller carried by the intermediate yoke 27. The relation of the arms 40 and 41 may be regulated by means of an adjustable screw 42 mounted in one of the arms and arranged to engage the other. Rigidly secured to the shaft 28 at one end of the main frame is an arm 43 and rigidly secured to the yoke for the sleeve 38 is an arm 44. (See Figs. 9 and 12). 130

The arms 43 and 44 constitute locking arms and each is provided at its lower end with a pin 45 arranged to be engaged by a nose or projection 46 extending upwardly from a second locking arm 47 mounted on a stud 48 carried by the adjacent end member of the main frame. The positions of the locking arms 47 are controlled by means of levers 49, mounted on the shaft 50 at the rear lower portion of the machine and extending forwardly to positions adjacent to the pressure rollers. The forward ends of the levers 49 are connected by means of links 51 with the respective locking arms 47. A spring 52 acts on each lever 49 to move the same upwardly and thereby hold the locking arm 47 in its operative position. When the pressure roller 22 is in its operative position the pin 45 on the locking arm 44 will lie in the path of the nose 46 and when the arm 47 moves upwardly the nose will engage the pin 45 and will remain in this position until the yoke has been retracted by the action of the cam 34, when the nose 46 will spring in front 25 of the pin 45 and lock the arm 44, the yoke 28, and pressure roller 22 in their retracted positions. The pressure rollers are released from the locking device by the action of the coin controlled mechanism which will be hereinafter described.

The amount of movement imparted to the stamp strips by the feed rollers is positively controlled by means of a controlling device having parts such as spring actuated pins, 35 adapted to enter openings formed in the strip between the adjacent articles. In the case of postage stamps these openings are in the form of a transverse series of perforations, while in tickets they frequently take the 40 form of notches in the lateral edges of the strip. Each controlling device, as here shown, comprises a frame or head 53 carried by an arm 54 which is pivotally mounted on a shaft 55 extending lengthwise of the 45 main frame in front of the guideways 17. Slidably mounted in the frame 53 are a plurality of pins 56 which are yieldably supported therein so that they will be retracted by contact with an unperforated portion of 50 the strip. In the present construction the frame or head 53 is provided with a series of guideways 57 in which are mounted a corresponding plurality of plungers 58 each carrying one of the pins 56. Springs 59 confined in the respective guideways between the plungers 58 and the ends of the guideways serve to press the pins outwardly, but these springs are very light and permit the pins to be easily retracted. Preferably the 55 pins 56 are greater in number than the number of perforations between adjacent stamps and are spaced apart a distance less than the distance between the adjacent perforations of the stamp strip. Consequently there will 60 always be two or more pins in line with the perforations in the stamp strip regardless of any lateral displacement of the strip with relation to the controlling device. The controlling device is mounted for movement about the axis of the shaft 55 and the walls 70 of the guideways 57 are provided with openings to permit the pins 56 to enter the guideways. The controlling device is held normally in its innermost position with the pins 56 in the perforations of the stamp strip and 75 when the machine is to be operated the controlling device for the strip of stamps, is automatically withdrawn to release the stamp strip and is retained in its retracted position until the stamp strip has been advanced 80 approximately the desired distance, but before the strip has completed its movement the controlling device is again moved inwardly and the pins 56 brought in contact with the face of the strip. The pressure 85 of the pins against the face of the strip will not appreciably affect its forward movement and as soon as the row of perforations is brought into line with the controlling device two or more of the pins 56 will enter 90 said perforations, thus positively checking the movement of the stamp strip. The controlling devices for the stamps of different denominations are separately controlled and to this end the arms 54 of the controlling 95 devices for the two one cent stamp strips are rigidly connected with the shaft 55 and are actuated thereby, while the controlling device for the two cent stamp strip is rigidly secured to a sleeve 60 loosely mounted on the shaft 55 and journaled in a bearing 61 in the main frame. This sleeve also constituting a bearing for the adjacent end of the shaft 55, the two parts being freely rotatable relatively one to the other. Rigidly 100 secured to the shaft 55 and the sleeve 60, beyond the respective frame members 1 and 2, are arms 62 which are acted upon by springs 63 to move the controlling devices inwardly and into operative engagement with the 105 stamp strips. Also connected with the shaft 55 and the sleeve 60, respectively, are rearwardly extending arms 64 which are connected by means of links 65 with the respective levers 49 which, as has been stated, are held normally in their retracted positions by springs 52. The connections between the arms 64 and the links 65 are preferably slideable and, as here shown, each link is provided with a slot 66 to receive a pin 67 carried by the corresponding arm 64. When either lever 49 is moved downwardly, as will 110 hereinafter appear, the corresponding controlling device will be moved outwardly into its inoperative position, as shown in Figs. 115 10 and 11.

The movements of the controlling devices into their inoperative and operative positions and the timing of these movements are controlled by suitable coin controlled mech- 120 125 130

anism, it being remembered that there are separate coin controlled mechanisms for the one cent stamps and for the two cent stamps. These coin controlled mechanisms are identical in construction and operation and each is adapted to receive either a nickel or a dime. The mechanism is of such a character that when a dime is deposited in one of the coin chutes and the mechanism operated the purchaser will receive either four two cent stamps or eight one cent stamps according to the denomination of the chute which he has selected. If a nickel is placed in either chute the purchaser will either receive two two cent stamps or four one cent stamps according to the denomination he has selected. It will be noted that the present machine is designed to sell stamps at a profit but it will be obvious that the mechanism can be readily adjusted to sell stamps or other articles at their face value. Each coin controlled mechanism comprises an actuating device which is operated from the cam shaft 33 and is operatively connected with the controlling device by a coin controlled member which is connected with the controlling device and which may be connected with the actuating device in either of two positions, depending upon whether the coin deposited was a five cent coin or a ten cent coin. This actuating device is here shown as an arm 68 rigidly secured to a shaft 69 mounted in the rear portion of the machine and is provided at its forward end with two depending fingers 70 and 71. Rigidly secured to the shaft 69 is an arm 72 extending downwardly and having at its lower end a contact roller 73 arranged to be engaged by a cam 74 secured to the cam shaft 33. The arrangement is such that the contact of the cam with the arm 72 will rock the shaft 69 about its axis and move the actuating arm 68 downwardly. The actuating arm 68 is connected with the controlling device by means of a coin controlled member here shown in the form of an arm 75 pivotally mounted at its lower end on the lever 49 and having at its upper end a lateral projection 76 adapted to be moved into line with either of the fingers 70 or 71 of the actuating arm. This arm 75 is provided with an offset portion 77 to permit it to pass about the cam shaft 33 and is also provided with a forwardly extending portion or finger 78 adapted to enter the vertical coin chute 10. A spring 79 acts upon the arm 75 to move the same normally to its rearmost position in which position the finger 78 will project into the coin chute and extend into the path of any coin which may be deposited in the chute. The arm 75 is preferably guided between guide members 80 and is here shown as provided with a rearward projection 81 constituting a stop to limit its rearward movement. When the arm is in its rearmost position with the fin-

ger 78 projecting into the coin chute the projection or stud 76 at the upper end thereof will be out of alignment with both fingers 70 and 71 of the actuating arm and consequently the movement of this arm will not be transmitted to the controlling device and the stamp strip will not be released. After the coin has been deposited in the chute and rests on the finger 78, as shown in Fig. 6, the crank 25 is operated, thus imparting movement both to the cam shaft 33 and to the positively driven feed rollers 21 but inasmuch as the pressure rollers 22 are locked in their inoperative positions the feed rollers do not function. The cam shaft 33 is provided with a cam projection or finger 82 arranged to engage the arm 75 and move the same forwardly against the tension of the spring 79, thus withdrawing the finger 78 from the coin chute and permitting the coin to move downwardly onto a stop 83 which projects through one of the side walls of the chute. The arrangement of the stop 83 is such that the coin resting upon the same will be supported in the path of the finger 78 of the arm 75 and when the cam projection 82 has moved out of engagement with the arm 75 and the latter is permitted to move rearwardly under the influence of the spring 79 the finger 78 will engage the coin and check the movement of the arm in a position determined by the diameter of the coin. If the coin is a ten cent coin the arm will be positioned with the projection 76 in line with the finger 70 of the actuating arm 68 and if the coin is a nickel the arm 75 will be positioned with the projection 76 in line with the other finger, 71, of the actuating arm. Should a penny be dropped into the chute the arm 75 will be positioned midway between the finger 70 and 71 and no connection will be established. Assuming that the coin in the chute is a dime the lever 75 will have assumed the position shown in Fig. 10 with the stud 76 in line with the finger 70 of the actuating arm and the further movement of the cam shaft will cause the cam 74 to act on the arm 72 to rock the shaft 69 and move the actuating arm 68 downwardly. This movement is transmitted through the connecting arm 75 to the lever 49 and the downward movement of the lever 49 actuates the locking arm 47 to release the yoke carrying the pressure roller 22, thereby permitting this roller to be moved by the action of the spring 29 into operative relation with the positively driven roller 21. The downward movement of the lever 49 is transmitted by the link or connecting bar 65 to the controlling device which is moved outwardly into the position shown in Fig. 10, thereby releasing the stamps and permitting them to be advanced by the feed rollers. By reference to Fig. 6, it will be noted that when the actuating

arm 68 is in its normal position, that is, its position prior to its operation, the projection 76 on the arm 75 when positioned by a dime will lie close to the finger 70 but when the arm is positioned by a nickel the projection will lie a considerable distance from the finger 71 so that the arm 68 will have an appreciable idle movement before the operation of the lever 75 takes place. Consequently the finger 70 will move the arm 75 downwardly a greater distance than will the finger 71. When the arm 75 is moved downwardly by the finger 71, that is, when it is positioned by a nickel, it is held in its lowered position until the cam 74 has cleared the roller 73 on the arm 72, at which time the actuating arm 68 is released and the arm 75 is moved upwardly by the spring actuated arm 49, thus permitting the controlling device 53 to be moved into engagement with the stamp strip by means of the spring 63. When a dime has been inserted in the coin chute the controlling device must be held out of engagement with the stamp strip for a greater length of time and, with the arrangement of parts here shown, the greater movement imparted to the connecting arm 75 by the finger 70 of the actuating arm will cause the lever 49 to move down far enough to permit a pin or locking stud 84 carried by the lever 49 to be engaged by a shoulder 85 on a locking arm 86 which is moved into such engagement with the pin 84 by a spring 87. The controlling device is thereby retained in its inoperative position after the cam 74 has moved out of engagement with the roller 73 and is retained in this position until the lever 49 is released from the locking device. To accomplish this the locking device or arm 86 has a trip finger 88 which extends into the path of a pin 89 carried by a rotatable part rigidly secured to the cam shaft 33. In the present instance, the pin 89 on one side of the machine is carried by the gear 37 and the pin 89 on the other side of the machine is carried by a cam disk 90, the purpose of which will be hereinafter described. The pin 89 is so arranged that it will move the locking arm 86 into an inoperative position just before the stamp strip completes its forward movement, thus enabling the controlling device to engage the face of the stamp before the line of perforations is brought into line therewith. When the lever 49 is released, either from the cam 74 or from the locking arm 86, the locking arm 47 will move upwardly and the nose 46 thereof will engage the pin 45 on the yoke locking arm 44 and will remain in this position until the cam shaft has further rotated and the cam 34 retracts the yoke and pressure roller, thus moving the pin 45 out of line with the nose 46 and permitting the latter to move into locking relation thereto, in which position it will remain until the coin controlled connecting arm 75 is again depressed. When the mechanism is controlled by a dime the cam 34 will retract the pressure roller 22 immediately after the controlling device 53 interrupts the movement of the stamp strip but when the mechanism is controlled by a nickel there will be a considerable interval of time between the engagement of the controlling device with the stamp strip and the retraction of the pressure roller 22. During this interval the feed rollers will slip on the stamp strip. The pressure exerted on the pressure roller 22 is very light as it is not necessary to tightly grip the stamp strip in order to advance the same. Due to this light pressure of the pressure roller and the rubber facing on the positively driven roller 21 the rollers will slip on the stamp strip without exerting thereon a pull strong enough to damage the same.

The guideways 17 for the stamp strips terminate just below the feed rollers and at the upper end of a delivery chute 90 which opens through the front wall of the cabinet 90. In the present machine a single delivery chute receives the stamps from all the guideways, but obviously a separate chute may be provided for each delivery mechanism if desired. Interposed between the upper end of the delivery chute 90 and the lower ends of the several guideways is a suitable cutter for severing from the strip or strips of stamps those stamps which are to be delivered. In the present construction, a single cutter operates on the three strips of stamps and if both delivery mechanisms have been simultaneously operated, as can be readily done by inserting a coin in both chutes, the stamps from all three strips will be severed at one time. As here shown, the cutting device comprises a fixed cutter bar 91 extending transversely to the several guideways and a blade 92 cooperating with the fixed cutting bar and extending for the full length thereof. This blade is secured at one end to a vertical shaft 93 journaled in suitable bearings on the main frame and acted upon by a spring 94 which tends to hold the blade normally in its inoperative position. As here shown, the spring 94 is coiled about the shaft 93 and is connected at one end with a collar 95 which is rigidly secured to the shaft and at the other end with a fixed part of the mechanism. Rigidly secured to the shaft 93 between its ends is a laterally projecting actuating arm 195 which is preferably provided with a roller 96 arranged to be actuated by the cam 90 on the cam shaft 33. This cam is provided with a short cam projection 97 which is so arranged that after the controlling device has entered the perforations on the stamp strip it will engage the roller 96 and rotate the shaft 93 in a direction to force the cutter blade 92 inwardly 130

and cause it to sever the several stamps which have been projected beyond the cutter bar. It will be noted that the cutting edge of the cutter bar 91 is spaced from the operative position of the pins 56 of the controlling device a distance equal, in the present instance, to two stamps, thus when the pins have entered the perforations in the strip, the perforations at the end of the stamp or stamps which are to be severed are in line with the cutting edge of the cutter bar and the line of severance will be along the row of perforations between the stamps. The cam 34 is preferably so arranged that the pressure roller 22 will be retracted prior to the cutting operation, thus leaving the stamp strip free and avoiding any likelihood of its buckling during the cutting operation.

The stop 83 which supports the coin in the coin chute is carried by a lever 98 pivotally mounted at its lower end, as shown at 99, and acted upon by a spring 100 which tends to move it inwardly so as to maintain the stop 83 in the path of the coin in the coin chute. The upper end of the lever 98 extends beyond the stop 83 and has an inwardly inclined portion 101 which lies in the path of a pin 102 secured to the end of the cam shaft 33 and arranged to engage the inclined portion 101 of the lever just prior to the completion of the rotation of the cam shaft thereby forcing the lever outwardly and withdrawing the stop 83 from the coin chute to permit the coin to drop through the chute and into a suitable coin receptacle. At this time the connecting arm 75 has been released and the finger 78 thereof will enter the coin chute as the coin which has been released drops out of the chute and will thus interrupt the movement of the following coin.

In Figs. 6, 10 and 11, I have illustrated one embodiment of the coin controlled selective mechanism but it will be understood that the principle embodied in this mechanism may take various forms and in Figs. 15, 16 and 17, I have shown a second embodiment of the idea. In the second form of the selective mechanism the mechanism is substantially the same as that above described but I have added thereto a device adapted to engage the coin in the chute and move the same against the coin controlled member 75, so as to move the latter outwardly a distance corresponding to the diameter of the coin and thus position the same with relation to the fingers 70 and 71 of the actuating device 68, the coin controlled member being positioned on its outward movement instead of on its inward movement as above described. The projection on the member 75, which enters the coin chute, is made somewhat shorter in the present instance, as shown at 103, and is preferably of

such a length that it extends into the opening in the wall of the chute but does not enter the passageway. Arranged on the opposite side of the chute and rigidly secured to a shaft 104 is an actuating member or arm 105 having at its lower end a projection 106 adapted to extend into the coin chute and engage the edge of the coin therein. This arm is acted upon by a spring 107 which is of a greater strength than the spring 79 which holds the coin controlled member 75 in its innermost position and will, therefore, when the arm 105 is free to move, exert pressure on the coin and cause the member 75 to be moved outwardly. The actuating member or arm 105 is controlled by a cam shaft 108 which acts on a second arm 109, also mounted on the shaft 104, and tends to rock the same in a direction to move the arm 105 outwardly. The cam 108 is so arranged that it will, upon the rotation of the shaft 33, first force the arm outwardly and withdraw the projection 106 from the chute and thereby release the coin and permit the same to drop onto the stop 83. After the coin has been released the cam will release the arm and permit the same to be moved inwardly by the spring 107, thereby causing the edge of the projection 106 to engage the coin and position the coin controlled member 105. In the present construction the projection 106 is provided at its upper edge with a nose 110 and the cam 108 is so shaped that the first portion of the movement thereof will withdraw the body of the projection from the chute but will permit the nose 110 to project into the path of the coin, thereby supporting the same until the stop 83 has been released and permitted to return to its operative position, the cam having a dwell to retain the projection in this position. After the stop has returned to its normal position the cam will impart a further outward movement to the projection 106 to release the coin before the arm and projection begin their inward movement. When the operation has been completed and the coin controlled member 75 released it will be returned to its normal position by the spring 79. This movement will be gradual and will be controlled by the arm 105 as the latter is moved outwardly by its cam.

While I have shown and described one embodiment of my invention I wish it to be understood that I do not desire to be limited to the details thereof as various modifications may occur to a person skilled in the art.

Having now fully described my invention what I claim as new and desire to secure by Letters Patent is:

1. In an apparatus of the character described, means for supporting a plurality of

strips of stamps, a pair of feed rollers for each strip of stamps, each pair of feed rollers comprising a positively driven roller, and a pressure roller, separate pivoted member for supporting the pressure roller of each pair of rollers, a spring acting on said supporting member to move said pressure roller into operative relation to its positively driven roller, means to retain each of said pressure rollers in its inoperative position, and separate coin controlled means to release the pressure roller for a selected strip of stamps.

2. In an apparatus of the character described, means for supporting three strips of stamps, a separate pair of feed rollers for each strip of stamps, each pair of feed rollers comprising a positively driven roller and a pressure roller, a separate member for supporting the pressure roller of each pair of rollers for movement toward and from the positively driven roller, springs acting on the respective supporting members to move said pressure rollers into operative relation with the positively driven rollers, each of said supporting members being movable relatively to the other, locking devices connected with two of said supporting members to retain the same in their retracted positions, one of said last mentioned supporting members having means acting on the third supporting member to also retain it in its retracted position, and separate coin controlled devices to actuate the respective locking devices.

3. In an apparatus of the character described, a pair of strip feeding rollers comprising a positively driven roller and a pressure roller movable toward and from said positively driven roller, means for retaining said pressure roller in its retracted position, and coin controlled means for causing said pressure roller to move toward said positively driven roller.

4. In an apparatus of the character described, a pair of strip feeding rollers comprising a positively driven roller and a pressure roller, a movable member supporting said pressure roller for movement toward and from the positively driven roller, a spring acting on said supporting member to move said roller toward said positively driven roller, a lock to retain said pressure roller in its retracted position, and coin controlled means for actuating said lock to release said roller.

5. In an apparatus of the character described, a pair of feeding rollers comprising a positively driven roller and a pressure roller, a movable member supporting said pressure roller, a spring acting on said supporting member to move said pressure roller toward said positively driven roller, a locking member connected with said supporting member, a spring actuated locking member

cooperating with the first mentioned locking member to retain said pressure roller in its retracted position, coin controlled means for disconnecting said locking members, and means for retracting said supporting member to permit the spring actuated locking member to operatively engage the first mentioned locking member.

6. In an apparatus of the character described, two pairs of feeding rollers, each pair comprising a positively driven roller and a pressure roller, movable members supporting the respective pressure rollers and mounted for independent movement about a common axis, springs acting on said supporting members to move said pressure rollers toward said positively driven rollers, means acting on one of said supporting members to retain the same in its retracted position, a part carried by said last mentioned supporting member and engaging the other supporting member to retain said last mentioned supporting member in its retracted position, and coin controlled means for actuating said retaining means to release said supporting members.

7. In an apparatus of the character described, a strip feeding device, a device to control the movement imparted to the strip by said feeding device, an actuating device for said controlling device, and a coin controlled member to operatively connect said controlling device with said actuating device and movable into different operative positions with relation to said actuating device.

8. In an apparatus of the character described, a strip feeding device, a device to control the amount of movement imparted to the strip by said feeding device, a coin controlled member operatively connected with said controlling device to impart movement thereto, said coin controlled member being movable into different operative positions, and an actuating device having parts to operatively engage said coin controlling member in said different positions thereof and to impart a different movement to said coin controlled member in each of said positions.

9. In an apparatus of the character described, a strip feeding device, a device to control the movement imparted to the strip by said feeding device, a lever connected with said controlling device, a coin controlled member connected with said lever and movable into different positions with relation thereto, and an actuating device having parts to respectively engage said coin controlled member in the different positions thereof and to impart a different movement to said coin controlled member in each of said positions.

10. In an apparatus of the character described, a strip feeding device, a device to control the movement imparted to the strip by said feeding device, an actuating device

having two contact portions, a lever operatively connected with said controlling device, a coin controlled member pivotally mounted on said lever and movable into operative relation to either of the contact portions of said actuating device.

11. In an apparatus of the character described, a strip feeding device, a device to control the movement of the strip by said strip feeding device, a coin chute, a coin controlled member operatively connected with said controlling device and having a part movable into and out of said coin chute, means tending to move said coin controlled member normally toward said coin chute, means for supporting a coin in said coin chute in the path of said part of said coin controlled member whereby said coin will control the position of said member, and an actuating device having means for engaging said coin controlled member in any one of a plurality of positions to impart movement thereto.

12. In an apparatus of the character described, a strip feeding device, a device to control the movement imparted to the strip by said strip feeding device, a lever connected with said controlling device, a coin controlled member pivotally connected with said lever and movable into different positions with relation thereto, an actuating device having parts to engage said coin controlled member in different positions thereof and to impart different movement to said coin controlled member in each of said positions, a lock to retain said coin controlled member in one of the positions to which it is moved by said actuating device, and means for disengaging said locking member from said coin controlled member after a predetermined operation of said feeding device.

13. In an apparatus of the character described, a strip feeding device, a device to control the movement imparted to the strip by said feeding device, a lever operatively connected with said controlling device, a coin chute, a coin controlled member pivotally mounted on said lever and having a part adapted to be moved into and out of said coin chute, a spring acting on said member to move said part into said coin chute, means for supporting a coin in said chute in the path of said part, whereby the position of said member will be controlled by said coin, and an actuating device having a plurality of projections arranged to engage said coin controlled member in different positions thereof and to impart different movements thereto.

14. In an apparatus of the character described, a strip feeding device, a device to control the movement imparted to the strip by said feeding device, a lever controlled by said feeding device, a coin chute, a coin controlled member pivotally mounted on

said lever and movable into and out of said coin chute, means for supporting a coin within said chute in the path of said part whereby the position of said member will be controlled by said coin, an actuating device having parts to engage said coin controlled member in either of a plurality of positions, one part of said actuating device being arranged to impart a greater movement to said coin controlled member than will be imparted by another part of said actuating device, a cam to operate said actuating device, and a locking device arranged to act on said coin controlled member when said greater movement has been imparted thereto and to retain the same in said position independently of said cam, and means for disengaging said locking device from said coin controlled member when a predetermined movement has been imparted to said feeding device.

15. In an apparatus of the character described, a pair of strip feeding rollers one of which is movable toward and from the other, a pivoted yoke to support said movable roller, a locking device to retain said yoke in its retracted position, a device to control the movement imparted to the strip by said feed rollers, a coin controlled member operatively connected with said controlling device and with the lock for said yoke, and an actuating device to impart movement to said coin controlled member.

16. In an apparatus of the character described, a pair of strip feeding rollers one of which is movable toward and from the other, a pivoted yoke to support said movable roller, a locking device to retain said yoke in its retracted position, a device to control the movement imparted to the strip by said feed rollers, a coin controlled member operatively connected with said controlling device and with the lock for said yoke, and an actuating device having a plurality of contacting portions, said coin controlled member being movable into line with either of said portions, said portions being so arranged with relation to said member that one of them will impart a greater movement thereto than the other.

17. In an apparatus of the character described, a pair of strip feeding rollers one of which is movable toward and from the other, a pivoted yoke to support said movable roller, a locking device to retain said yoke in its retracted position, a device to control the movement imparted to the strip by said feed rollers, a coin controlled member operatively connected with said controlling device and with the lock for said yoke, an actuating device having a plurality of contacting portions, said coin controlled member being movable into line with either of said portions, said portions being so arranged with relation to said

member that one of them will impart a greater movement thereto than the other, means acting on said coin controlled member when said greater movement has been 5 imparted thereto to retain the same against return movement, a cam to operate said actuating device, and means to release said coin controlled member for return movement after said cam has completed the 10 operation of said actuating device.

18. In an apparatus of the character described, strip feeding rollers one of which is movable toward and from the other, a pivoted yoke to support one of said rollers, 15 means acting on said yoke to move said roller toward the other roller of said pair, a locking device acting on said yoke to hold said roller in its retracted position, a device to control the movement imparted 20 to the strip by said feed rollers, a lever operatively connected with said controlling device and with the lock for said yoke, a coin chute, coin controlled member pivotally mounted on said lever and having a 25 part adapted to enter said coin chute, a spring acting on said lever to move said part toward the coin chute, means for supporting a coin in said coin chute in the path of said part, whereby the position of said 30 member will be determined by said coin, and an actuating device having parts to engage said coin controlled member in any one of a plurality of positions and to impart different movements thereto.

35 19. In an apparatus of the character described, a strip feeding device and a device to control the movement imparted to the strip by said feeding device and comprising a frame pivotally mounted for 40 movement toward and from said strip, contact members yieldably mounted in said frame and adapted to engage said strip, and coin controlled means for actuating said controlling device.

45 20. In an apparatus of the character described, means for supporting a strip of articles which are separated one from the other by openings, a feeding device for advancing said strip of articles, a frame 50 mounted for movement toward and from said strip, a plurality of pins yieldably mounted in said frame and adapted to engage said strip when said frame is moved toward the same, whereby a portion of said 55 pins will enter openings in said strip, and coin controlled means for actuating said frame.

21. In an apparatus of the character described, means for supporting a strip of 60 articles separated one from the other by rows of perforations, feeding means for advancing said strip of articles, a frame mounted for movement toward and from said strip, a series of pins yieldably mounted 65 in said frame, said pins being greater in

number than the perforations in said strip, and being spaced apart distances less than the distances between said perforations, and coin controlled means for actuating said frame.

22. In an apparatus of the character described, means for supporting a strip of articles separated one from the other by openings, feeding devices for advancing said strip, a frame pivotally mounted for movement toward and from said strip, said frame having a plurality of guideways, a spring actuated plunger mounted in each of said guideways, a pin carried by each plunger and projecting beyond said frame to engage said strip when said frame is moved toward the same, and coin controlled means for actuating said frame.

23. In an apparatus of the character described, a vertically arranged guideway, 85 means for supporting a roll of stamps at the upper end of said guideway, means for feeding said stamps through said guideway, a coin-controlled device to control the movement imparted to said stamps by said feeding means, a delivery chute communicating with the lower end of said guideway, a cutting device interposed between guideway and said delivery chute and comprising a 90 blade mounted on a vertical axis, a spring acting on said blade to move it in one direction, and a cam acting on said blade to move the same in the other direction.

24. In an apparatus of the character described, vertically arranged guideways, 100 means for supporting a roll of stamps at the upper end of each guideway, means for feeding said stamps through said guideways, a coin controlled device to control the movement imparted to said stamps by said feeding means, a delivery chute communicating with the lower end of said guideways, a cutting device interposed between the guideways and said delivery chute comprising a 105 fixed cutter bar, a vertical shaft rotatably mounted at one end of said bar, a cutter blade carried by said shaft and cooperating with said cutter bar, a spring acting on said shaft to move said blade into its inoperative position, an arm secured to said shaft, and a 110 cam acting on said arm to impart operative movement to said blade.

25. In an apparatus of the character described, a plurality of vertical guideways, 115 means for supporting a corresponding plurality of strips of stamps at the upper ends of said guideways, a plurality of pairs of feed rollers acting on the respective strips to feed the same through said guideways, one roller of each pair being positively driven and the positively driven rollers of the several pairs being rotated in unison by a common actuating device, yokes supporting the other rollers of said pairs of rollers, the several yokes being pivotally mounted for 120 125 130

dependent movement on a common axis, springs acting on the respective yokes to move the rollers toward the corresponding positively driven rollers, a cam shaft extending through said yokes, an operative connection between said cam shaft and the actuating device for said feed rollers, cams carried by said cam shaft and acting on the respective yokes to retract the same, and coin controlled means to retain said yokes in their retracted positions.

26. In an apparatus of the character described, a plurality of vertical guideways, means for supporting a corresponding plurality of strips of stamps at the upper end of said guideways, a plurality of pairs of feed rollers acting on the respective strips to feed the same through said guideways, one roller of each pair being positively driven and the 20 positively driven rollers of the several pairs being rotated in unison by a common actuating device, yokes supporting the other rollers of said pairs of rollers, the several yokes being pivotally mounted for independent movement on a common axis, springs acting on the respective yokes to move the rollers toward the corresponding positively driven rollers, a cam shaft extending through the said yokes, an operative connection between said cam shaft and the actuating device for said feed rollers, cams carried by said cam shaft and acting on the respective yokes to retract the same, separate devices to control the movement of the 30 respective stamp strips by said feeding rollers, a cam mounted on said cam shaft to actuate the several controlling devices, and coin controlled means to control the connections between said cam and said controlling devices.

27. In an apparatus of the character described, a plurality of pairs of strip feeding rollers, one roller of each pair being movable toward and from the other roller of that pair, independently movable structures 45 for supporting the respective movable rollers, springs acting on said structures to move the rollers carried thereby into operative relation with the other rollers of the respective pairs, a cam shaft, cams carried by said shaft and acting on said structures to retract the same, separate devices to control the movement imparted to the strips by the respective feeding rollers, a cam mounted on said 50 cam shaft to actuate the several controlling devices, and coin controlled means to control the connection between said cam and said controlling devices.

28. In an apparatus of the character described, a plurality of pairs of strip feeding rollers, one roller of each pair being movable toward and from the other, a separate cam to actuate each of said movable rollers, separate devices to control the movement of the strips 60 by the respective pairs of feed rollers, a

plurality of cam operated actuating devices, and separate coin controlled means for connecting said actuating devices with the respective controlling devices and for controlling the movement of said controlling devices.

29. In an apparatus of the character described, a strip feeding device, a device to control the movement imparted to the strip by said feeding device, an actuating device having two contact portions, and a coin controlled member operatively connected with said controlling device and having a part movable into operative relation with either of the contact portions of said actuating device.

30. In an apparatus of the character described, a strip feeding device, a device to control the movement imparted to the strip by said feeding device, an actuating device, and a coin controlled member operatively connected with said controlling device and having a part movable into different positions with relation to said actuating device, whereby the latter will impart different movements to said coin controlled member.

31. In an apparatus of the character described, a strip feeding device, a device to control the movement imparted to the strip by said feeding device, an actuating device, a coin chute having means to support a coin within the same, and a member operatively connected with said controlling device and having a part movable into different operative positions with relation to said actuating device and also having a part to engage said coin and thereby position said member with relation to said actuating device.

32. In an apparatus of the character described, a strip feeding device, a device to control the movement imparted to the strip by said feeding device, an actuating device, a coin chute having means to support a coin within the same, a member operatively connected with said controlling device and having a part movable into different operative positions with relation to said actuating device and also having a part to engage said coin and thereby position said member with relation to said actuating device, a second member to engage said coin and impart movement to the coin and the first mentioned member, and means to actuate said second member.

33. In an apparatus of the character described, a strip feeding device, a device to control the movement imparted to the strip by said feeding device, an actuating device, a coin chute having means to support a coin within the same, a member operatively connected with said controlling device and having a part movable into different operative positions with relation to said actuating device and also having a part to engage said coin and thereby position said member with

relation to said actuating device, an arm movably mounted on that side of said chute opposite said coin controlled member and having a part adapted to enter said chute and engage said coin, and means to actuate said arm to cause said coin controlled member to be actuated.

34. In an apparatus of the character described, a strip feeding device, a device to control the movement imparted to the strip by said feeding device, an actuating device, a coin chute having means to support a coin within the same, a member operatively connected with said controlling device and having a part movable into different operative positions with relation to said actuating device and also having a part to engage said coin and thereby position said member with relation to said actuating device, an arm movably mounted on that side of said chute opposite said coin controlled member and having a part adapted to enter said chute and engage said coin, a spring to impart inward movement to said arm, and a cam to move said arm outwardly against the tension of said spring.

35. In an apparatus of the character described, a strip feeding device, a device to control the movement imparted to the strip by said feeding device, an actuating device, a coin chute having openings in the opposite edges thereof, a stop arranged to support a coin within said chute in line with said openings, a member operatively connected with said controlling device and having a part movable into different operative positions with relation to said actuating device and also having a part arranged adjacent to the opening in one edge of said chute, an arm pivotally mounted adjacent to said chute and having a part adapted to enter the opening in the other edge of said chute, and means to actuate said arm.

36. In an apparatus of the character described, a strip feeding device, a device to control the movement imparted to the strip by said feeding device, an actuating device, a coin chute having openings in the opposite edges thereof, a stop arranged to support a coin within said chute in line with said openings, a member operatively connected with said controlling device and having a part movable into different operative positions with relation to said actuating device and also having a part arranged adjacent to the opening in one edge of said chute, an arm pivotally mounted adjacent to said chute and having a part adapted to enter the opening in the other edge of said chute, said projection having an inwardly extending nose arranged above that portion thereof which contacts with the coin, a spring to move said arm in one direction, and a cam acting on said arm to first withdraw the body of the projection from said chute with-

out withdrawing said nose and to then withdraw the nose from the chute.

37. In an apparatus of the character described, a coin controlled selective mechanism comprising a coin chute having means to support a coin therein, an actuating device, and a member operatively connected with a part to be selectively controlled and having a part movable into different operative positions with relation to said actuating device, said member also having a part to engage a coin in said chute and thereby position the first mentioned part of said member with relation to said actuating device.

38. In an apparatus of the character described, coin controlled selective mechanism comprising a coin chute having means to support a coin therein, an actuating device having two contact portions, and a member operatively connected with a part to be selectively controlled and having a part movable into operative relation to either of the contact portions of said actuating device, said member also having a part to engage a coin in said chute and thereby position the first mentioned part of said member with relation to the contact portions of said actuating device.

39. In an apparatus of the character described, a coin controlled selective mechanism comprising a coin chute having means to support a coin therein, an actuating device, a member operatively connected with a part to be selectively controlled and having a part movable into different operative positions with relation to said actuating device, said member also having a part to engage a coin in said chute, a second member movably mounted adjacent to said coin chute and having a part arranged to engage a coin in said chute and move said coin and the first mentioned member to position the latter with relation to said actuating device, and means to actuate said last mentioned member.

40. In an apparatus of the character described, a pair of strip feeding rollers comprising a driven roller and a pressure roller, a pivoted yoke having two arms, one of said arms supporting said pressure roller for movement toward and from said driven roller, a spring acting on the other arm of said yoke to move said pressure roller toward said driven roller, and coin controlled means to control the position of said pressure roller with relation to said driven roller.

41. In an apparatus of the character described, a pair of strip feeding rollers comprising a driven roller and a pressure roller, a pivoted yoke having two arms, one of said arms supporting said pressure roller for movement toward and from said driven roller, a spring acting on the other arm of said yoke to move said pressure roller toward said driven roller, means to retract said

pressure roller, a lock to retain said pressure roller in its retracted position, and coin controlled means for actuating said lock to release said pressure roller.

42. In an apparatus of the character described, a pair of strip feeding rollers comprising a driven roller and a pressure roller, a pivoted yoke having two arms, one of said arms supporting said pressure roller for movement toward and from said driven roller, a spring acting on the other arm of said yoke to move said pressure roller toward said driven roller, a device acting on the last mentioned arm of said yoke to retract said pressure roller, a lock to retain said pressure roller in its retracted position, and coin controlled means for actuating said lock to release said pressure roller.

43. In an apparatus of the character described, a pair of strip feeding rollers comprising a driven roller and a pressure roller, a pivoted yoke having two arms, one of said arms supporting said pressure roller for movement toward and from said driven roller, a spring acting on the other arm of said yoke to move said pressure roller toward said driven roller, a shaft extending between the arms of said yoke, a cam carried by said shaft and acting on said yoke to retract said pressure roller, a lock to retain said pressure roller in its retracted position, and coin controlled means for actuating said lock to release said pressure roller.

44. In an apparatus of the character described, means for supporting a plurality of strips of stamps, a pair of feed rollers for

each strip of stamps, each pair of feed rollers comprising a driven roller and a pressure roller, a plurality of pivoted yokes each having two arms, one arm of each yoke supporting the pressure roller of one pair of rollers, springs acting on the other arms of the respective yokes to move said pressure rollers toward the corresponding driven rollers, cams arranged between the arms of the respective yokes and acting thereon to retract said pressure rollers, separate means to retain the several pressure rollers in their retracted positions, and coin controlled means to release said pressure rollers for movement toward the corresponding driven rollers.

45. In an apparatus of the character described, means for supporting a plurality of strips of stamps, a pair of feed rollers for each strip of stamps, each pair of feed rollers comprising a driven roller and a pressure roller, a plurality of pivoted yokes each having two arms, one arm of each yoke supporting the pressure roller of one pair of rollers, springs acting on the other arms of the respective yokes to move said pressure rollers toward the corresponding driven rollers, a shaft extending between the arms of the several yokes, cams secured to said shafts and arranged to act on the respective yokes to retract said pressure rollers, locking means for the respective pressure rollers, and coin controlled means for actuating said locking means to release said pressure rollers.

In testimony whereof, I affix my signature hereto.

ALBERT B. VARBLE.
